CLAIM

The ornamental design for a crank bait fishing lure, as shown and described.

DESCRIPTION

FIG. 1 is a perspective view of the crank bait fishing lure of the present invention;

FIG. 2 is a side elevation of the lure of FIG. 1;

FIG. 3 is a front elevation of the lure as viewed in line with the forwardly extending lip flange of the lure of FIG. 2;

FIG. 4 is a bottom view of the lure of FIG. 1; and

FIG. 5 is a plan view of the lure of FIG. 1.
